WASHBOARD

Charles T. Gilbert, Saginaw, Mich., assignor to
National Washboard Company, Chicago, Ill., a
corporation of West Virginia

Application May 9, 1934, Serial No. 724,700

2 Claims.

(Cl. 68—29)

This invention relates to improvements in the parts of washboards employed as rubbing faces and more particularly to double faced washboards.

5 The object of my invention is the provision of a novel and improved double rubbing face that shall be inexpensive and simple in construction and capable of being made of light material, such as thin sheets of metal, yet rigid to resist, without undue springing or bending, the stresses that are produced by bearing down and rubbing when in use.

10 The claimed invention consists principally of an improved arrangement of two corrugated sheets formed and co-operating so that each rubbing face of the wash-board will provide a substantially equal degree of stiffness and rigidity for the other rubbing face and also to present surfaces of different working characteristics, one 15 for washing ordinary goods, the other for delicate fabrics. The corrugations of the first mentioned sheet extend across the direction of rubbing and of the other substantially lengthwise thereof. The sheets are secured together back 20 to back in bearing engagement at the crossings and present mutually supporting elements arranged in grid-like pattern that provides symmetry and equivalence of bracing for both rubbing faces.

25 30 Heretofore double wash-boards with sheet metal rubbing faces have had their faces provided with longitudinal ribs, and the two sheets have been placed back to back with their longitudinal ribs parallel and in contact lengthwise. Such arrangement produced a double-faced board that was resistant to bending along lines extending from the top edge of the board to the bottom, but the two sets of ribs, being parallel and contiguous, afforded practically no resistance to bending 35 along lines extending across the board from one upright edge to the other, and consequently produced unequal degrees of bracing, or what may be termed non-symmetrical bracing for the two rubbing faces.

40 45 The means by which I have remedied such defects of earlier double-faced boards will now be described, reference being had to the accompanying drawing, in which:

50 Fig. 1 is a front face view of a wash-board embodying my invention.

Fig. 2 is a rear view of the same, partly broken away.

55 Fig. 3 is a central vertical section on line 3—3 of Fig. 2.

Fig. 4 is a horizontal sectional view on line 4—4 of Fig. 3.

Fig. 5 is a fragmentary view in perspective showing the preferred arrangement of the contiguous rubbing faces.

Fig. 6 is a detail view in perspective, showing an approved method of assembling the two rubbing faces as a unit.

The same numerals of reference are used to designate corresponding parts in the several views.

10 The rectangular frame of the wash-board is composed of the side bars 1 and 2, and the top cross-bar 3, bottom cross-bar 4 and intermediate cross-bar 5, and may be of the usual or any suitable construction.

15 The rubbing element of my improved and novel construction is seated at its side edges in suitably shaped grooves in the side-bars 1 and 2 of the frame, at its top edge in the grooved intermediate cross-bar 5, and at its bottom edge in the grooved bottom cross-bar 4. In the construction shown the rubbing element is composed of two corrugated sheets 6, 7 of thin sheet metal laid back to back. Each sheet is formed, as by corrugating, 20 to present parallel series of alternating work-engaging ridges or ribs 8 and work-engaging channels, troughs, or grooves 9 in the form of similar arrises, uniformly spaced or substantially so. In addition the sheets may be embossed in known manner. The sheets are disposed so that the arrises of one cross those of the other. In the example herein shown they are perpendicular, to give point contacts, but they may cross at any other suitable angle appropriate to attain the results herein set forth.

25 30 Under the normal stresses of use each channel wall or groove, as 9 of one face presents a transverse beam-like support for all or most of the several channel walls of the other faces. Each corrugated sheet is thus supported at a great number of approximately equidistant points spaced closely together over its entire area. Each such point of support rests upon a channel wall of the opposing sheet and that wall is in effect 35 a beam extending from edge to edge of the rubbing face. Otherwise stated, the surfaces of the two sheets are preferably in the form of uniform or similar arrises or corrugations mutually perpendicular to give only point contacts or bearings.

40 45 The embodiment here shown as a preferred form of my invention has equally spaced point bearings or contacts at the crossings arranged in what may be termed a symmetrical gridlike pattern by which the two sheets are equally braced 50 55

in both directions, and they are held together so as to constitute a unit that is rigid in itself.

Preferably the two sheets 6 and 7 are arranged as shown, the ridges and grooves of one sheet 5 being at right angles to those of the other and in bearing arrangement therewith.

In Fig. 6, showing an enlarged fragmentary view, the edges 10, 11 of the two sheets are shown attached by folding so as to lap over one upon 10 the other. By thus fixing together two or more edges of the two superimposed sheets the double working surface 6, 7 can be fabricated so as to constitute a unitary double-faced rubbing element, and these units can be easily and quickly 15 inserted in the frame when the wash-board is being assembled.

Another advantage is attained by the arrangement of the corrugated rubbing surfaces as above described. The horizontally arranged corruga- 20 tions of sheet 7 are well adapted for washing most kinds of goods, but the vertical arrangement of corrugations in sheet 6 is especially well adapted for washing fine fabrics, such as linen handkerchiefs, silk lingerie, etc.

The wash-board above described is inexpensive in construction and the rubbing surfaces are exceedingly strong, but light, both sheets together weighing less than the single sheet of an ordinary board with one rubbing face wherein 30 the metal has to be made thick enough to withstand bending both laterally and vertically.

The unitary construction indicated in Fig. 6 facilitates manufacture and replacement, and the wash-board has numerous advantages as an 35 article of manufacture in addition to the desirable features above described.

An improved means for binding and securing

the edges of the two sheets together is disclosed and claimed in co-pending application Serial No. 737,484, filed July 30, 1934, by Charles W. Saden- water, common assignee.

Having thus described my invention, what I 5 claim and desire to secure by Letters Patent is:

1. In a wash-board, two rubbing faces made of corrugated sheet metal, each presenting similar alternating work-engaging arris shaped ridges and channels substantially uniformly spaced, 10 said sheets being secured in back to back engagement, the ridges and channels of each sheet extending across those of the other sheet substantially at right angles to give mutual contacts substantially equi-distant and defining a 15 grid-like pattern, each channel of one sheet con- 20 stituting a transverse supporting member for each of the several channels of the other sheet when the latter is subjected to stresses incident to its use as a rubbing surface.

2. In a wash-board, two rubbing faces, one adapted for washing ordinary goods, in which the corrugations extend substantially perpendicular to the direction of rubbing, the other for delicate fabrics, in which the corrugations extend sub- 25 substantially lengthwise of the direction of rubbing, said faces being made of corrugated sheet metal secured together, the two presenting similar sub- 30 stantially uniformly spaced ridges and channels, the channels of each sheet being arranged sub- stantially perpendicular to those of the other sheet and in bearing engagement therewith at the crossings, and constituting transverse sup- 35 ports therefor arranged in grid-like patterns to provide symmetry of bracing for both rubbing faces.

CHARLES T. GILBERT.
